UNITED STATES PATENT OFFICE.

WILLIAM WILLARD KELLY, OF CLEVELAND, OHIO.

DESIGN FOR A SALES RACK.

Application filed February 20, 1924. Serial No. 8,685. Term of patent 14 years.

To all whom it may concern:

Be it known that I, WILLIAM W. KELLY, a citizen of the United States, residing at Cleveland, in the county of Cuyahoga and State of Ohio, have invented a new, original, and ornamental Design for a Sales Rack, of which the following is a specification, reference being had to the accompanying drawing, forming part thereof.

The figure is a perspective view of a sales rack, showing my new design.

I claim:

The ornamental design for a sales rack, substantially as shown.

In testimony, that I claim the foregoing as my own, I have hereto affixed my signature.

WILLIAM WILLARD KELLY.
